UNITED STATES PATENT OFFICE.

WILLIAM WARREN PUTNAM, OF BLOOMER, ASSIGNOR OF TWO-THIRDS TO
G. W. SPUGLE AND J. H. RANEY, BOTH OF AUBURN, ARKANSAS.

CAR-COUPING.

SPECIFICATION forming part of Letters Patent No. 403,071, dated May 7, 1889.

Application filed December 31, 1888. Serial No. 295,099. (No model.)

To all whom it may concern:

Be it known that I, WILLIAM WARREN PUTNAM, a citizen of the United States, residing at Bloomer, in the county of Sebastian and State 5 of Arkansas, have invented a certain new and useful Improvement in Car-Couplers; and I do hereby declare the following to be a full, clear, and exact description of the invention, such as will enable others skilled in the art 10 to which it appertains to make and use the same.

The object of this improvement is a car-coupler that will connect automatically with couplers of similar construction, that may be 15 operated from the ground or from the top of the car for the purpose of disconnection, and that may be used in connection with couplers of ordinary form. These results are attained by the mechanism illustrated in the drawings 20 herewith filed as part hereof, in which the same letters of reference denote the same parts in the different views.

Figure 1 is a front elevation of a car-coupler embodying the features of my improvement. Fig. 2 is a side elevation of the same 25 with parts removed. Fig. 3 is a transverse section with parts removed. Fig. 4 is a view of the link inverted. Fig. 5 is a side view of a modification of the link represented in Fig. 30 4. Fig. 6 is a side view of one of the parts detached. Fig. 7 is a top view of the same.

A is the draw-bar, having an ordinary bumper-head, A', recessed lateral projections A², transversely-perforated vertical extensions a a', and a vertically-perforated arc, a², all made integral. The recessed lateral extensions A² are provided with correspondingly-sized clutch-blocks B B', having curved points b b at their inner ends, and provided 35 centrally with flared slots b², for a purpose hereinafter set forth. The transversely-perforated vertical extensions a a' operate as studs or fulcrums for levers C C', pivoted thereto, as shown at c c in Figs. 1 and 2, and 40 arranged to engage with the clutch-blocks B B' through slots a³ in the top of the draw-bar, and flared slots b² b² in the clutch-blocks B B', more fully illustrated in Figs. 2, 3, and 7.

D D' are springs secured at their lower

flanged ends by means of bolts d d to the 50 draw-bar lateral extensions A², and provided at their upper ends with flanges d', which engage with the inner edges of the levers C C' and hold them in the position shown.

E is a shaft having an operating-wheel, E', 55 and provided with a shoulder, f, below which it is extended through the perforation in the arc a² into a correspondingly-sized socket in the top of the draw-bar A, and is thereby supported in the position shown, which is to be 60 additionally secured by a suitable number of staples or otherwise to the end of the car, above the top of which the shaft E is to be extended.

G G' represent chains or other pliable means 65 connecting the levers C C' with the shaft E in a way that will cause the levers to move inward when the shaft E is turned in the proper direction, which will cause the clutch-blocks B B' to move outward.

H is a bar or link having barbed heads H², provided with inclined or curved bottoms h and vertical perforations h', for a purpose hereinafter set forth.

K is a bent link, of similar construction 75 otherwise,

M is an ordinary link-pin, for the reception of which the draw-bar is provided with a perforation, substantially as shown by the position of the pin M in Fig. 2.

When the link H is inserted in the draw-bar, the clutch-blocks B B' will be moved laterally by contact with and passage of the link-head between them, after which the springs D D' will secure the connection by forcing 85 the clutch-blocks back to the positions shown in Fig. 1. When the link is attached to a car moving toward another provided with a similarly-constructed coupler, the curved bottom h of the link-head H' will engage with the 90 mouth or curved entrance A' of the draw-bar, and the operation described for the clutch-blocks will ensue automatically.

By reason of the perforations h' in the link-heads H' the pin M can be used in connection 95 therewith for coupling purposes should the automatic mechanism become disabled; or an ordinary link could be used for coupling the

mechanism with an ordinary draw-bar. The 5 bent link K is to be used when there is a difference in the height of the cars to be connected. By reason of the shaft E the clutch-blocks B B' can be operated for uncoupling from the top of the car; or the levers C C' may be adjusted from the ground by hand for the same purpose.

Having explained the construction and operation of my improvement, what I claim as new, and desire to secure by Letters Patent, is—

10 In a car-coupler, the combination, with a draw-bar A, having the head A' and the recessed lateral extensions A², of the clutch-blocks B B', located in the recesses of said extensions, and having curved points b b and

flaring slots b², the levers C C', pivoted to extensions upon the upper surface of the draw-bar, the lower ends of the levers engaging the 20 slots in the clutch-blocks, springs D D', secured at their lower ends to the lateral extensions A² and engaging the upper ends of the levers C C' and the vertical operating-shaft E, and the chains connecting the upper 25 ends of the levers with said operating-shaft, substantially as described.

In testimony whereof I affix my signature in presence of two witnesses.

WILLIAM WARREN PUTNAM.
